GEORGE W. DAUGHERTY, OF WILMINGTON, DELAWARE.

Letters Patent No. 103,995, dated June 7, 1870.

IMPROVEMENT IN SPOOLING-MACHINES.

The Schedule referred to in these Letters Patent and making part of the same

To all whom it may concern:

Be it known that I, GEORGE W. DAUGHERTY, of the city of Wilmington, in the county of New Castle and State of Delaware, have invented a new and improved Spooling-Machine; and I do hereby declare that the following is a full, clear, and exact description of the construction and operation of the same, reference being had to the annexed drawing making a part of this specification, in which—

Figure 1 is a front view of a machine embodying my invention.

Figure 2 is an elevation showing that end of the machine which is at the right hand, in fig. 1.

Figure 3 is a vertical transverse section, showing those parts of the machine at the left hand of the line Z Z, drawn across fig. 1.

Figure 4 is the side of the spool-holder and stand.

Figure 5 is a plane view of the spool-holder and stand.

Figure 6 is the finger, with its spring foot.

Figure 7 is the guide or traversing-rail, with guide-pulley and finger, with its spring foot.

Nature and Objects of the Invention.

The first part of my invention consists in a spool-stand so constructed and arranged as to enable the operator to raise the spool-holder from the drum or cylinder, and leave it at rest whenever the broken yarn is to be pieced or the spool removed.

The second part of my invention consists of the thread-guide, with a traveling rail, which is worked by a quadrant or cog-wheel, so as to cause a traversing of the bobbin-rail. The thread-guide, being constructed with the V-shape, in two pieces, and curved, cuts or shaves the foreign matter incorporated in the yarn, without breaking the thread, and permits the motes and seeds to drop from it, thereby avoiding clogging in the split of the guide. This guide, being constructed of two blades set in place by a screw, is easily adjusted to suit any size of thread. The object of this part of my invention is to lay the thread evenly upon the spool.

The third part of my invention consists of the combination of a quadrant with a guide or traverse-rail. The object of this part of my invention is to give the operator the entire control of the length of sweep or stroke of the traverse, thereby enabling him to adjust his traverse to any required length, the quadrant having this advantage over the wheel, in that, being composed of two pieces, it permits the arm to be lengthened or shortened sufficiently to carry the stroke the distance required.

General Description.

A is the frame of the machine.

B is the driving-pulley operating the machine.

C is the spool-holder, pivoted to and working upon

the stand D, which is so constructed and arranged as to receive and hold it at rest by means of a beveled lug, T, and corresponding shoulder U on the holder.

When the operator desires to disengage the spool from the cylinder S, the holder C is thrown at rest by the hand, and operated in no other way, except when in motion and in contact with the cylinder S.

E is the thread-guide, of a sickle-like shape, constructed with two blades, and attached to the traversing rail K by a set-screw, so as to regulate the slit or opening, as shown in the drawing, for the purpose of cleansing or freeing the thread from foreign substances, preventing their passage to the spool, and turning out a perfect thread. The curved or sickle shape of the guide produces a shearing-like action, which readily and at once throws off the foreign substance from the guide, and prevents it becoming choked. In the straight guide the foreign substance very frequently chokes the slit or opening, and causes the thread to break; in the angular the choking is not so frequent while in the shape shown.

I know V-shaped guides have been heretofore used, and I do not claim the V-shape; but the alteration of the shape of the guide is not a mere change of appearance, but really a substitute for the original or old-shaped guide.

F is the ordinary bobbin-finger, operated by a spiral spring, G, in place of the weight ordinarily used.

H is the quadrant operating the guide or traversing rail K, and adjustable radially, giving the operator the entire control of the sweep or stroke of the traverse, which the ordinary wheel will not permit.

L is the swift or reel, which may be attached whenever it is desired to spool hank-yarn.

M is the guide for spooling from the swift.

What I claim as my invention is—

1. The spool-holder C, provided with a shoulder, U, in combination with the stand D, having a beveled lug, T, for the purpose of enabling the spool-holder to be thrown at rest, substantially as and for the purposes mentioned.

2. The curved thread-guide E, constructed and operating substantially as and for the purposes aforesaid.

3. The adjustable segmental rack H, in combination with the traveling bobbin-rail K, as and for the purposes described.

4. The combination with the spool-holder C and stand D, the thread-guide E and sprung bobbin-finger F, of the quadrant or adjustable segmental rack H, cog-wheel traversing bobbin-rail K, and mangle L, constructed, arranged, and working substantially as and for the purposes hereinbefore set forth.

GEORGE W. DAUGHERTY.
